TEST TUBE STORAGE RACK OR
SIMILAR ARTICLE

Samuel M. Broadwin, New York, N.Y., assignor to Maryland Plastics Incorporated, New York, N.Y., a corporation of Maryland

Filed Dec. 27, 1965, Ser. No. 323

Term of patent 14 years

(Cl. D16—1)

FIGURE 1 is a perspective view of one side of a test tube storage rack or similar article, showing my new design; and

FIGURE 2 is a perspective view thereof from the other side.

I claim:

The ornamental design for a test tube storage rack or similar article, substantially as shown.
